UNITED STATES PATENT OFFICE.

ABRAM SMELLIE HAMILTON, OF NANAIMO, BRITISH COLUMBIA, CANADA.

DETONATOR-MAGAZINE.

1,038,355.

Specification of Letters Patent. Patented Sept. 10, 1912.

Application filed August 18, 1911. Serial No. 644,793.

To all whom it may concern:

Be it known that I, ABRAM S. HAMILTON, citizen of the Dominion of Canada, residing at Nanaimo, in the Province of British Columbia, Canada, have invented a new and useful Detonator-Magazine, of which the following is a specification.

This invention relates to a box for carrying detonator caps, such as are used in conjunction with a fuse in blast firing, and the device is designed to meet the requirements of the various governments in providing a locked box or magazine in which these caps may be safely carried by the "firing boss" or other authorized person and from which they may be delivered, one at a time, as required.

In a recent application, at present pending before the Office, application was made on a rotatable magazine wherein the detonator compartments were introduced radially from the circumferential surface of the container. In this application the compartments are introduced from an end face of the magazine and their axes are parallel to the axis of rotation, by which means a larger number of compartments may be provided within the same dimension of magazine and a simpler mechanism can be applied for delivering the detonators and for locking the closure thereafter.

The invention is particularly described in the following specification, reference being made to the drawings by which it is accompanied, in which:

Figure 1 is a vertical section through the device, Fig. 2 is a face view detached, of the magazine body, Fig. 3, a similar view of its cover inverted, Figs. 4 and 5, similar views showing the successive movements of the shutter in opening the two delivery apertures, and Fig. 6, a view of the lever key by which the closing shutter is opened.

In these drawings 2 represents an annular magazine body one face of which is provided with a closed end 3 and in the other face is introduced a series of detonator compartments 4. These are preferably arranged in concentric rings. The open ends of these compartments 4 are closed with a cover 6 rotatably mounted on a pin 10 which pin is also the screw which secures the cover on the magazine body. The head of the screw by which the pivot pin is withdrawn and the cover released, is sunk in a recess 9 so that it requires a special key to remove the

cover, which key will only be in the possession of authorized persons. The cover 6 is provided with an aperture 7 and 8 for each ring of detonator compartments 4 in the body 2 and these apertures 7 and 8 of the cover are closable by a segmental shutter 11 which is rotatably mounted on the under side of the cover 6 and is normally held in the closed position against a stop pin 12 by a spring 13 one end of which is secured to the shutter and the other to the cover 6.

The shutter 11 is so arranged that the delivery apertures 7 and 8 are not open simultaneously, one opening before the other and closing again when further rotation of the shutter uncovers the other. To effect this the shutter on one side is provided with an aperture 14 which is brought into register with the aperture 8 of the cover by an angular movement of the shutter less than required to uncover the aperture 7 of the cover and when further movement is made to uncover 7 the aperture 14 has moved out of register and 8 is closed.

As the delivery of the detonators is required to be under the control of authorized parties only, the shutter 11 is opened with a lever key 15, see Fig. 6, the operating end 16 of which is inserted in a key hole 17 provided in the cover 6 and will engage and rotate the shutter when turned as indicated in Figs. 3, 4 and 5. The lever handle of the key, when the key is inserted, lies parallel to the face of 6 and projects slightly beyond its rim so that it may be manipulated to open the desired aperture 7 or 8 and at the same time the cover 6 may be rotated to bring that aperture 7 or 8 in register with a detonator compartment.

A simple, convenient and effective magazine is thus provided within which the detonators are safely retained each in a separate compartment and normally inaccessible to any except the authorized person carrying the key, by whom the detonators may be removed as required, one at a time.

Having now particularly described my invention and the manner of its use, I hereby declare that what I claim as new and desire to be protected in by Letters Patent, is:

1. A detonator magazine comprising a body having a set of detonator compartments parallel to its axis, a cover swivelly mounted on said body to close said compartments, said cover having apertures which may be brought in register with the

several detonator compartments, a shutter normally closing the cover apertures, means continuously tending to move said shutter to its aperture closing position, said shutter 5 having a key receiving portion and said cover having a key hole slot, and a key mounted on said cover and having a portion to enter said key hole slot and engage said shutter to move the same to open said cover apertures.

2. A detonator magazine comprising a body having a set of detonator compartments parallel to its axis and having a central chamber, a lug projecting upwardly into 15 said central chamber, a cover mounted over said body to form a closure for said chamber, said cover having a depending hollow lug alining with said body lug, and a screw passing swivelly through said hollow lug 20 into said body lug to swivelly connect said cover to said body, said cover having apertures which may be brought into register with the several detonator compartments, said cover having an inner recess, a shutter 25 mounted swivelly on said hollow lug to normally close the cover apertures, a spring mounted beneath said cover and held in said central chamber for continuously tending to move said shutter to its aperture closing 30 position, and means for moving said shutter to its aperture opening position.

3. A detonator magazine comprising a body having a set of detonator compartments

parallel to its axis and having a central chamber, a lug projecting upwardly 35 into said central chamber, a cover mounted over said body to form a closure for said chamber, said cover having a depending hollow lug alining with said body lug, and a screw passing swivelly through said hollow lug 40 into said body lug to swivelly connect said cover to said body, said cover having apertures which may be brought into register with the several detonator compartments, said cover having an inner recess, a 45 shutter mounted swivelly on said hollow lug to normally close the cover apertures, a spring mounted beneath said cover and held in said central chamber for continuously tending to move said shutter to its aperture closing position, and means for moving said shutter to its aperture opening position, said last named means comprising a key, said cover having a key hole slot through which said key may be inserted, said shutter having a key receiving recess and a shoulder to coöperate with said key in virtue of which 50 said shutter may be moved by said key.

In testimony whereof I have signed my name to this specification in the presence 55 of two subscribing witnesses.

ABRAM SMELLIE HAMILTON.
